UNITED STATES PATENT OFFICE.

WILLIAM GEGENHEIMER, OF BALDWIN, AND ERNEST E. BARNEY, OF PORT WASHINGTON, NEW YORK.

GRIPPER FOR OFFSET PRINTING PRESSES.

Application filed December 5, 1925. Serial No. 73,390.

This invention relates to gripper mechanism for removing a printed sheet from the impression or feed cylinder of a press, particularly an offset press. In such apparatus 5 a plurality of fingers are employed to periodically seize the sheets as the impressions are completed thereon during the rotation of the feed cylinder, the sheets being removed from the latter and carried to the stack.

10 In the usual types of such gripper mechanism, the fingers are carried by a gripper-shaft arranging parallel with a so-called saddle-shaft having projections in register with the fingers so that the sheet is seized 15 between the fingers and the said projections. The gripper-shaft is oscillated by a cam when the fingers come into register with the sheet so that the fingers are moved into contact with the latter, a reverse oscillation of the 20 shaft taking place when the sheet is released, at the stack.

Customarily, the gripper shaft is spring-actuated to carry the fingers toward the 25 projections of the saddle shaft. A recognized necessity in such case is exact adjustment of the fingers upon the gripper-shaft so that none of the fingers shall be in advance of other fingers of the set, because, in such case, the last named fingers would 30 be inactive or only partially active, that is to say, they would not grip the paper or would grip the paper with insufficient force. Another difficulty is that even when the 35 fingers are adjusted to exact position, the spring of the saddle-shaft itself or the gripper-shaft is frequently such that some of the fingers received the full tension of the gripper-shaft spring to the exclusion of other fingers and the sheet is unevenly pulled and 40 frequently torn.

Attempts have been made to impel the fingers by means of springs acting supplementary to the gripper shaft spring, but this has not solved the difficulty, because such 45 springs have acted to neutralize the effect of the gripper-shaft spring and exact adjustment of the fingers still is necessary, which adjustment is in practice seldom achieved for various reasons including the "springing" of the saddle-shaft from the centre towards its ends through the pressure of the fingers. The object of the present invention 50 is to overcome the various stated defects in gripper mechanism.

55 The invention will be understood by ref-

erence to the accompanying drawings in which—

Figure 1 is a plan view of associated gripper and saddle shafts and other gripper elements, two gripper fingers being shown, and 60

Figure 2 is a transverse section on the line 2—2, Figure 1.

Referring to the drawings, the gripper-shaft A is shown with part of its length broken away and two gripping fingers only 65 mounted thereon. The gripper shaft is mounted in the bearings 1 and it is parallel with the saddle-shaft B journaled in bearings 2, the saddle-shaft also being shown broken away. The saddle-shaft is provided 70 with the projections or saddles 3 in register with the gripper fingers 4. Each gripper finger is formed as a curved projection from a circular base 4^x, which partially encircles, and is mounted upon, the gripper-shaft A 75 for free oscillation thereon. The base 4^x of the gripper finger is placed intermediate the two spaced halves of an actuating sleeve 5, the said halves being joined by a head C providing an upper shoulder c^x and a lower shoulder c^{xx} adapted to contact with the spaced ends of the finger base member 4^x, as illustrated in Figure 2.

Each finger is provided with a lever 6 connected with a link rod 7, the latter passing through an aperture formed in a fulcrum plate 8 secured by screw stud 9 to the saddle-shaft B. A spring encircles link rod 7 and bears against fulcrum plate 8, the tension of the spring being regulated by a nut 10 threaded upon the link rod. The action 85 of the spring in bearing upon fulcrum plate 8, which is fixed and rigid, is such that the tension of the spring is thrown upon the link rod through nut 10 and the rod acts 90 to move the gripper finger in the direction of the arrow, Figure 2.

In Figure 2 of the drawings, the parts are shown in the active position of the gripper fingers and it will be seen that the gripping 100 functions of the latter are entirely independent of the gripper shaft. When the moment for release of the sheet is reached, the gripper shaft is rotated counter-clockwise and carries with it the actuating sleeve, by reason of the fact that the head of the latter is fixed upon the shaft by means of screw 11. When the gripper fingers are in action, there is sufficient clearance between shoulder c^{xx} and the finger base member to en- 105 110

able free and unhampered action of the spring 12, and thus the gripper-shaft has a slight counter-clockwise turn before shoulder c^{xx} reaches the base of the finger and then turns the finger with the shaft, raising it from the saddle and the sheet theretofore gripped.

In our improvements the gripper-shaft spring may be entirely eliminated and it is only necessary that a predetermined minimum tension be placed upon all the springs 12 of a set of grippers in order to insure entire satisfactory operation of the device. The fact that some of the springs may be at greater than the minimum tension so as to compel their appropriate gripper fingers to seize the sheet with more than necessary force, is of no moment due to the fact that in our improvements lack of exact adjustment of one finger does not react upon the other fingers as in the devices now in use. Any springing of the shafts by the pressure of the fingers is eliminated by the fact that such pressure is neutralized by the counter-pressure of the springs upon the saddle-shaft through fulcrum plate 8. The arrangement is such that the springs act equally upon the fingers and the saddle-shaft, tending to move them toward each other.

Having described our invention what we claim and desire to secure by Letters Patent is as follows:

1. Gripper mechanism for printing presses, comprising a gripper shaft, a gripper finger loosely mounted on said shaft, an actuating sleeve for said finger, a saddle-shaft, an actuating spring for said gripper finger and means carried by the saddle-shaft and engaging the spring whereby the action of said spring will tend to move the finger and saddle-shaft toward each other.

2. Gripper mechanism for printing presses comprising a gripper shaft, a gripper finger mounted on said shaft, a saddle-

shaft, a fulcrum plate on said saddle-shaft, and a spring reacting against the fulcrum plate and connected to the gripper finger, said spring being adapted to move the gripper finger toward the saddle-shaft.

3. In grippers for printing presses, a gripper finger formed with a partially circular base adapted for mounting upon a gripper shaft, an actuating sleeve for said gripper finger, a lever arm connected to the gripper finger, a link rod connected to the lever arm, and a spring upon the link rod and adapted to move said rod lengthwise against the resistance of a member of the press.

4. Gripper mechanism for printing presses comprising a gripper finger adapted for mounting on a gripper shaft, an actuating sleeve adapted to be fixed to the gripper shaft and having a shoulder for engaging the gripper finger, a lever arm connected to the gripper finger, a link rod connected to the lever, a fulcrum plate having an aperture adapted to receive the link rod and adapted to be secured to the saddle shaft of a press, a spring surrounding the link rod intermediate its free end and the fulcrum plate, and an adjusting member carried by the link rod and adapted to adjust the tension of the spring.

5. In printing press feed mechanism comprising a gripper shaft and a saddle-shaft, a gripper finger adapted for oscillation upon the gripper shaft, a device for actuating the finger, and spring acting means adapted to simultaneously impose pressure upon the gripper finger in a direction toward the saddle-shaft and pressure upon the saddle-shaft in a direction toward the gripper finger.

In testimony whereof, we have signed our names to this specification.

WILLIAM GEGENHEIMER.
ERNEST E. BARNEY.
